BOILER

Paul R. Delling, Haddonfield, N. J., and Hans W. Lindemann, Gary, Ind.; said Lindemann as signor to said Delling

Application October 16, 1929. Serial No. 399,973

1 Claim. (Cl. 122—115)

The invention relates to improvements in boiler construction.

This boiler construction is especially adapted for steam generation for high pressure service 5 for steam driven road vehicles.

The object is to provide a boiler of maximum strength and minimum weight, both of which characteristics being extremely important for such service.

10 Referring to the drawing, which illustrates merely by way of example suitable means for effecting the invention:—

Fig. 1 is an elevation of the boiler on the plane of line 1, 1 of Fig. 2.

15 Fig. 2 is a section on the line 2, 2 of Fig. 1.

Figs. 3, 4 and 5 are sectional details on an enlarged scale.

Similar numerals refer to similar parts throughout the several views.

20 The barrel or cylinder 9 of the boiler preferably comprises a section of hammer-welded steel tubing. To each end of this barrel 9 is welded, as at 10, a flanged header, such as 11 and 12. Over each welded seam, a steel ring 13 is shrunk,

25 and the ring is also welded, as at 14 and 15, to the boiler barrel and to the header, see Fig. 3. The advantage of this construction is that the welded seams are thus reinforced by the rings and the welding associated therewith.

30 Approximately the upper third of the boiler, under working conditions, contains steam and is not exposed to the fire. This part of the boiler therefore is not provided with fire tubes. In order to give this part of the boiler the required 35 strength, a steel casting 16, with heavy and deep flanges 17, is riveted to the inner side of each header 11 and 12, and heavy steel stay bolts 18 are threaded at each end into both the casting 16 and into the adjacent header. These stay

40 bolts run from end to end of the boiler. To prevent leakage through the threads of the stay bolts, and as further reinforcement, nuts 19 are

threaded on the outer ends of the stay bolts with copper washers 20 interposed between the nuts and the headers. The barrel of the boiler is wound with the proper number of layers of piano wires, as at 21 (the number of layers depending upon the diameter and working pressure of the boiler) and this wire winding is covered with a layer of heat insulating material 22. The outside of the boiler is covered or enclosed with a non-corrosive metal sheeting 23, such as aluminum.

By the use of hammer-welded tubing and flanged headers in the construction of the boiler, expensive dies, which were necessary for former high-pressure fire tube boilers of similar construction, such as the Stanley boiler, are eliminated, and great latitude is given in the size of the boiler, as hammer-welded steel tubing is commercially available at from eight inches to ninety-six inches diameter. The flanged headers 75 are spun and are thus available in almost any diameter without the use of a die.

While the welding of barrel to headers would ordinarily secure a strong construction, and the shrinking of a ring over this weld will serve as 80 a substantial reinforcement, the welding of the ring both to the header and the barrel gives a double reinforcement which renders the resistance of the boiler to very high pressure unusually effective.

85 What we claim is:—

A steam boiler, comprising a barrel and a header having an annular flange abutting the barrel end, with a weld joining said abutting ends, a ring enclosing and shrunk upon said abutting 90 ends and a weld joining one side of the ring with the header and a weld joining the other side of the ring with the barrel, as and for the purpose described.

PAUL R. DELLING. 95
HANS W. LINDEMANN.
